UNITED STATES PATENT OFFICE.

CASSIN SNYDER, OF PHILADELPHIA, PENNSYLVANIA.

FIRE-EXTINGUISHER.

1,048,751.

Specification of Letters Patent.

Patented Dec. 31, 1912.

Application filed December 8, 1911. Serial No. 664,528.

To all whom it may concern:

Be it known that I, CASSIN SNYDER, a citizen of the United States, residing in the city of Philadelphia, county of Philadelphia, and State of Pennsylvania, have invented certain new and useful Improvements in Fire-Extinguishers, of which the following is a specification.

My invention relates to apparatus, such as a fire extinguisher, in which any suitable material may be stored and discharged and directed at the will of the operator.

My invention resides in a fire extinguisher, or like apparatus, in which a plunger or piston is held locked or restrained in opposition to a spring or like device, together with means for releasing the plunger which then forces out of a chamber the material contained therein.

20 My invention resides in the apparatus hereinafter described and claimed.

For an illustration of one of the forms my invention may take, reference is to be had to the accompanying drawing, in which:

25 Figure 1 is a longitudinal, sectional view, some parts in elevation, of my improved apparatus. Fig. 2 is a side elevational view of a plunger setting tool or device. Fig. 3 is a transverse sectional view, some parts shown in elevation, taken on the line, and looking in the direction of the arrows, A—A of Fig. 1.

30 A casing or chamber 1, of any suitable form or cross section, and of any suitable material, such as metallic tubing or the like, is provided with the end caps 2 and 3. The cap 2 is provided with a central boss 4 screw-threaded at 5 to receive a stop cock or valve 6 having the usual handle or grip 7. The boss 4 is further screw-threaded at 8, in an aperture of smaller diameter than the screw-threaded hole 5. At the other end of the chamber 1 the cap 3 has a central boss 9 screw-threaded at 10 to receive the screw-

35 threaded enlargement 11 upon the handle 12. A pin 13 extends through this enlargement 11 and through the rod 14, whereby the handle 12 and its part 11 are secured upon the rod 14. The rod 14 passes freely through the hole 15 of smaller diameter than the screw-threaded part 11. A pin 16 is secured to the rod 14 and extends therethrough at a distance from the hole 15. Secured by pin 17^a to the rod 14 is a screw-threaded piece or enlargement 17 engaging in the screw-threaded aperture in the main

piston or plunger member 18. To guide the screw-threaded part 17 to its coaxing screw-threaded hole in the member 18, the member 18 is flared or suitably tapered at 19. The member 18 has a flange 20 between which and the member 21 is clamped the piston or plunger packing 22 of any suitable flexible or yielding material such as leather, fabric, or the like. The member 21 has a screw-threaded nipple 23 engaging in a screw-threaded hole in the member 18, for so clamping the member 22. The member 21 is countersunk at 24 and in the outer face of the member 21 is inserted the ring 25 70 having the hole or aperture 26.

Between the plunger or piston and the cap 3 is disposed the spiral spring 27 shown compressed in Fig. 1. In front of the piston or plunger and within the chamber 1 is confined the fire extinguishing fluid 28 or other material to be ejected from the chamber 1. 75

When the chamber 1 is empty and the plunger or piston at the extreme right end, as viewed in Fig. 1, the apparatus may be 80 prepared for charging and use as follows: By removing the valve or stop cock 6, the screw-threaded hole 8 is uncovered and adapted to receive the screw-threaded rod 29, Fig. 2, having the handle 30 for turning the same and having at its other end the nose 31. The rod 29 is screwed into and through the screw-threaded hole 8 in the cap 2, and the nose 31 passes through the aperture 26 in the ring 25 and engages against the 90 member 21, secured, as above stated, to the main piston or plunger member. As the rod 29 is turned it advances through the hole 8 and forces the plunger or piston toward the left, as viewed in Fig. 1, thereby compressing the 95 spring 27. This operation is continued until the plunger reaches the position shown in Fig. 1, where the spring 27 is preferably fully compressed. The rod 29 has, however, been 100 previously unscrewed, so that the screw-threaded part 11 of the handle 12 is to the left of and outside of the screw-threaded hole 10. It is now inserted, and the end 17 on the rod 29 is guided by the flange portion 19 to the screw-threaded hole in the 105 member 18. As the handle 12 is turned, the screw-threaded portion 17 engages in the screw-threaded hole in the member 18 and simultaneously the threaded portion 11 on the handle 12 engages in the screw-threaded 110 hole 10 in the boss 9 on cap 3. The turning of the handle 12 is continued until the parts

2
 assume the position shown in Fig. 1, and when this position is reached the aperture 15 is fully closed by the screw-threaded plug 11 and the plunger member 18 is securely held by the rod 14. Now the rod 29 is removed and the plunger is held locked in the position shown in Fig. 1. After the removal of the rod 29 the material 28 is introduced into the chamber 1, and then the stop cock or valve 6 is replaced and the handle 7 turned to the shut-off position. If, now, it is desired to eject the material 28 from the chamber 1, the handle 12 and rod 14 are unscrewed, thus releasing the plunger or piston member 18, whereupon the spring 27 expands tending to force the plunger toward the right. And if the handle 7 of the stop cock is turned to the flow position, the spring expands and forces the plunger toward the right, forcing out through the valve 6 the material 28, which is then directed or applied at the will of the operator. After the plunger has been released from the rod 14, the pin 16 on the rod 14, being longer than the diameter of the hole 15, prevents the rod from having too much play with respect to the cap 3.

What I claim is:

1. In a fire extinguisher, the combination with a chamber, of a piston movable therein, means for propelling said piston, means independent of said propelling means for locking said piston in retracted position comprising a rod adapted to engage and hold said piston, a cap on said chamber, said cap having a perforation through which said rod extends, a handle on said rod outside of said cap, said locking means also including means for detachably securing said rod to said cap and to said piston simultaneously.
2. In a fire extinguisher, the combination with a chamber, of a piston movable therein, means for propelling said piston, a screw-threaded rod adapted to engage and hold said piston, a cap on said chamber, said cap having a perforation through which said rod extends, a handle on said rod outside of said cap, and further screw-threads upon said rod adapted to engage said cap as the screw threads on said rod engage said piston, said piston when free from said rod being moved independently of said rod by said propelling means.
3. In a fire extinguisher, the combination with a chamber, a cap on said chamber, a rod extending through said cap, a handle on said rod, means on said rod for detachably locking said rod to said piston for holding the same in retracted position, and means on said rod for detachably securing the same to said cap, the movement of said handle detaching said rod from said piston and said cap simultaneously, and means for moving said piston independently of said rod.
4. In a fire extinguisher, the combination with a chamber, of a piston therein, means for locking said piston in retracted position comprising a rod threaded to said chamber and to said piston, means for actuating said rod to disengage the same from said piston and from said chamber simultaneously, and means for propelling said piston in said chamber independently of said rod after detachment from said rod.
5. In a fire extinguisher, the combination with a chamber, of a piston movable therein, means for moving said piston, means for locking said piston in retracted position comprising a rod adapted to detachably engage and hold said piston, a cap on said chamber, said cap having a perforation through which said rod extends, a handle on said rod outside of said cap, and means for securing said rod to said cap as said rod is being secured to said piston.
6. In a fire extinguisher, the combination with a chamber, of a piston movable therein, means for moving said piston, means for locking said piston in retracted position comprising a rod adapted to engage and hold said piston, a cap on said chamber, said cap having a perforation through which said rod extends, a handle on said rod outside of said cap, means simultaneously actuated by said handle for attaching said rod to said cap and to said piston, and means for permitting limited motion of said rod with respect to said cap when said rod is disengaged from said piston.
7. In a fire extinguisher, the combination with a chamber, of a piston therein, means for locking said piston comprising a rod detachably secured simultaneously to said chamber and to said piston by the same movement of said rod, and means in said chamber for propelling said piston independently of said rod after disengagement from said rod.

In testimony whereof I have hereunto affixed my signature in the presence of the two subscribing witnesses.

CASSIN SNYDER.
